HYDRAULIC HEAT REGULATOR

Mark Olson, Detroit, Mich.

Application June 27, 1935, Serial No. 28,783

3 Claims. (Cl. 236—84)

This invention relates to a hydraulic heat regulator, the general object of the invention being to provide means for regulating the draft of a heating plant through the means of a thermostat controlling another means which controls the flow of water to a cylinder, the piston of which operates the dampers of the heating plant, whereby the heat in the room of a building is kept automatically at a predetermined temperature.

This invention also consists in certain other features of construction and in the combination and arrangement of several parts, to be herein-after fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is an elevation of the invention.

Figure 2 is a top plan view of Figure 1 with parts omitted.

Figure 3 is a perspective view of the magnet operated means.

Figure 4 is a view of the lever controlled by said means.

Figure 5 is a perspective view of the double switch member.

Figure 6 is a view of one of the lever actuating members and the member to which it is hinged.

Figure 7 is a view of one of the other lever operating members.

Figure 8 is a diagrammatic perspective view of the apparatus.

Figure 9 is a view of one of the other switches.

In these drawings the letter A indicates the supporting frame for the apparatus and this frame with the parts carried thereby is enclosed in a casing B shown in dotted lines in Figure 1.

A cylinder 1 is supported by the frame and contains a piston 2, the rod 3 of which extends through one end of the cylinder and has attached to its outer end the elongated cross-head 4.

A pipe 5 is connected to the water system and the flow of water through this pipe is regulated by the valve 6 shown in Figure 1. Branch pipes 7 lead from this pipe 5 to the ends of the cylinder 1 and each pipe contains a valve 8 to which an arm 9 is connected. Exhaust pipes 10 are also connected to the ends of the cylinder and these exhaust pipes connected with a discharge pipe 11 which may lead to a drain or which may be connected to a spray for spraying the coal in the bin. Each exhaust pipe 10 has a valve 12 there-

in and an arm 13 connected to the valve and a rod 14 connects the arm 13 of the exhaust pipe leading from one end of the cylinder to the arm 9 of the inlet valve of the pipe 7 which leads to the opposite end of the cylinder, as shown in Figure 8, so that when an inlet valve is opened to permit water to flow into one end of the cylinder the outlet valve of the discharge pipe connected with the opposite end of the cylinder is opened so that water can enter one end of the cylinder to move the piston in one direction and the water in front of the piston can discharge through the exhaust pipe at the opposite end of the cylinder.

A bellcrank lever 15 is pivotally supported on a bracket 16 attached to a large bracket 17 supported from the frame A and one arm of the bellcrank lever is adjustably connected to a loop 18, as shown in Figure 8 and this loop is connected by the flexible members 19 with the dampers of the heating plant so that the movement of the bellcrank controls the dampers to regulate the heat. A link 20 connects the other arm of the bellcrank lever 15 with a projection 21 on the cross-head. Thus the movement of the piston 2 in the cylinder 1 under the action of the water will move the cross-head and said movement of the cross-head will operate the bellcrank lever to control the dampers of the heating plant.

The cross-head slides on the rods 22 supported in the frame and said cross-head is formed with the upwardly extending ears 23 and a projection 24 extending at one end thereof.

A substantially channel-shaped member 25 is connected by spring hinge 26 to a bracket 27 attached to the underside of a partition member 28 which extends horizontally across the frame, said member 25 and the parts associated therewith being shown in Figure 7. This member 25 is provided with the outwardly extending wings 29 at its sides and with an inclined part 30 at its lower free end. One wing 29 is adapted to engage a lever 31 pivoted at 32 on the axis of the hinge on the member 25 and the lower end of the lever is connected by a link 33 with an ear 23 of the cross-head and the upper end of the lever is connected by a spring 34 with the lower end of a lever 35 pivoted to the frame at 36 so that when this lever is moved to one direction by the cross-head the spring 34 will be tensioned.

A second channel-shaped member 37, similar to the member 25, is connected by a spring hinge to the supporting bracket 38 attached to an under-part of the partition 28 and this member 37 is arranged opposite the member 25 and a lever 39 has

its upper end forked and pivoted to the hinge pin of the member 37 and the lower end of this lever is connected by a link 40 to another ear 23 of the cross-head, the outer prong of the forked end of the lever 39 is longer than the other prong and this long prong is connected to the lower end of the lever 35 by a spring 41 which is tensioned by movement of the lever 39 by the cross-head, the parts being so arranged that when the cross-head moves in one direction the spring 34 will be tensioned while the spring 41 will be contracted and then when the cross-head moves in the opposite direction the spring 41 will be tensioned while the spring 34 is contracted. Thus these parts will act to cause the springs to move the lever 35 in one direction or the other, in accordance with which spring is tensioned and after the lever 35 has been released by the latch means which includes a pin 42 on the upper end of the lever 35 which fits in an opening 43 in a lever 44 pivoted at its upper end to a part of the frame as shown at 45. The opening 43 has an enlarged lower part and a slot-like upper part, the upper part acting to hold the lever 35 against movement when the pin is in the slot-like part and as the lever 44 swings from one side to the other the pin 42 will enter the enlarged part and thus the lever 35 tends to swing on its pivot. A latch lever 46 is normally held in engagement with one side or the other of the lower end of the lever 44 by a spring 47. Said latch lever moves downwardly to releasing position by the armature 48 of the magnetic means 49, when circuit to said means is closed and when this occurs the lever 35 will be swung by that spring 34 or 41 which is tensioned and this swinging movement of the lever 35 will swing the lever 44 on the opposite side of the latch lever 46 and then the latch lever returns to normal position to hold the parts in their new positions.

The armature lever 48 is connected to the latch lever 46 by a link 50 and a conductor 51 connects the magnetic means with a battery 52, the other side of the magnetic means being grounded as shown at 53. The opposite side of the battery is connected to the thermostatic means 54, one terminal 55 of which is connected by a conductor 56 with a normally closed switch 57 and this switch is connected by a conductor 58 with a spring switch 59 which is engaged by the member 37 when said member is swung toward the cylinder, this member 37 being grounded. The other terminal 60 of the thermostat is connected by a conductor 61 with a normally closed switch 62 and this switch 62 is connected by a conductor 63 with a spring switch 64 adapted to be engaged by the member 25 when such member 25 swings away from the cylinder 1. These switches 59 and 64 are constructed and arranged as shown in Figure 1 and are supported and insulated from the bracket 65 which depends from the partition 28. Thus when the member 37 is in contact with the switch 59 and the thermostat is in contact with the terminal 55 the circuit to the magnetic means will be closed and when the thermostat is in contact with the terminal 60 and the member 25 is in contact with the switch 64 the thermostat will close the circuit to the magnetic means. A dog 66 controlled by a spring 67 is adapted to hold the member 25 against movement by its spring hinge and a link 68 connects this dog with a bell-crank 69 to which is connected a rod 70 slidably supported in the frame and having an adjustable collar 71 thereon for engagement by the projection 24 on the cross-head so that when the piston

2 moves toward the right in Figure 8 the projection 24 will strike the collar 71 and thus shift the rod 70 which will cause the bellcrank 69 and the link 68 to move the dog 66 to releasing position.

A similar spring controlled dog 72 is provided for the channel-shaped member 37, this dog being normally held in holding position by a spring 73 and a link 74 connects the dog to a bellcrank 75 which is connected to a rod 76 slidably arranged in the frame and having an adjustable collar 77 thereon which is also engaged by the projection 24 of the cross-head when the piston moves to the left so that the dog 72 is moved to releasing position when the cross-head is moved to the left.

A wing 29' on the channel-shaped member 37 engages the lever 39 and the opposite wing 29' of this member 37 is adapted to engage the lower end of a lever 80 pivoted intermediate its end to a part of the frame as shown at 81 and said lower end of the lever 80 is connected by a link 82 to the arm 9 of one of the inlet valves 8. The other wing 29 of the channel-shaped member 25 is adapted to engage a lever 83 pivoted intermediate its end as shown at 84 and the lower end of this lever 83 is connected by a link 85 with an arm 13 of one of the exhaust valves 12.

A pair of oppositely arranged substantially channel-shaped members 86 and 87 are each connected by a spring hinge 88 with a supporting bracket 89, see Figure 6, to the partition member 28, these members extending upwardly above the partition member and each member is provided with the side wings 90 and each member at its lower end carries a projection 91 of non-conductive material for separating the parts of the switches 57 and 62. The member 86 is held in retracted position by a dog 92 and the member 87 is held in retracted position by a dog 93, each channel-shaped member having an inclined bar 94 thereon for enabling it to pass the dog after which the dog swings downwardly and holds the member in retracted position. The dog 92 is carried by a shaft 95 having an arm 96 attached thereto which is connected by a link 97 with the lever above the pivotal point 36 of said lever. The dog 93 is attached to a shaft 98 which has an arm 99 thereon connected by a link 100 with the lever 35 above the pivotal point 50 thereof. Each of the arms 96 and 99 is freely rotatable on the shaft but said arm will rotate the shaft when pressed against a projection on an arm 101 fastened to the shaft. Each dog is moved to engaging position by a spring 102 and has one end fastened to each arm 101 and its other end to a part of the frame.

One of the wings 90 of the member 86 is adapted to engage the upper end of the lever 83 while a similar wing of the member 87 is adapted to engage the upper end of the lever 80. The other wing of the member 86 is adapted to engage the upper part of a lever 103 which is connected by a link 104 with an ear of the cross-head while the other wing of the member 87 is adapted to engage the upper end of a lever 105 which is connected by a link 106 to another ear of the cross-head. The pivotal points of the levers 83 and 103 are in alignment with the hinge pin of the member 86 and if desired these levers can be pivoted on extended ends of said member 86 and the levers 80 and 105 are arranged in the same manner with respect to the member 87.

With the parts in the position shown in Figure 8 all the valves are closed and of course the circuit

is broken by the thermostat being in an intermediate position. However, if the temperature in the room in which the thermostat is located should change sufficiently to cause the thermostat 5 to contact the terminal 55 for instance, it being understood that the device is so connected with the dampers as to cause this action, the circuit will be closed and current will pass from the battery through the thermostat, the terminal 10 55, conductor 56, switch 57, conductor 58, switch 59, the member 37 and through the magnetic means 49 to the battery. Thus the armature 48 will be lowered which will swing the latch lever 46 to releasing position and as the spring 34 is contracted and the spring 41 under tension the lever 35 will be swung on its pivot 36 by said spring 41 so that the pin 42 will swing the lever 44 to the left in Figure 8 so that said lever 44 will be on the opposite side of the latch lever as shown in Figure 3. This movement of the lever 35 will release the dog 92 through means of the link 97, arm 96 pushing against arm 101 to rock the shaft 95. Thus the member 86 will swing to the right under the action of the spring hinge and this movement will cause one of the wings 90 to engage the lever 83 and rock the same on its pivot and through means of the link 85 and the link 14 the inlet valve 8 and exhaust valve 12 will be open so that water will enter the left hand end of the cylinder and the water in the other end pass through the exhaust. Thus the piston will be moved to the right, forcing the cross-head to the right and this movement of the cross-head will rock the lever 31 which will tension the spring 34 and the lever 39 which releases tension on the spring 41 and thus the lever 35 will be moved until the lever 44 strikes the left hand side of the latch lever 46 when the parts will be held in the position shown in Figure 3. As the member 86 moves to the right the switch breaking part 91 thereof will open the switch 57 so as to break the circuit. This movement to the right of the cross-head also shifts the levers 103 and 105, the movement of the lever 103 acting to return the member 86 into engagement with the dog 92 and the movement of the lever 105, swinging away from the member 87 permitting future movement to the left of said member 87. When the cross-head reaches the limit of this movement to the right the projection 24 engaging the collar 71 will move the rod 70 and through the bellcrank 69 the link 68 will move the dog 66 to releasing position which permits the member 25 to swing forwardly so that one of the wings 29 engaging the lower end of the lever 83 will move said lever 83 to a position where the links 85 and 14 will close the inlet and exhaust valves that have been open so that the parts will come to rest with the piston 2 at the right hand end of the cylinder and of course the movement of the cross-head will have changed the dampers. The parts are now in a position to operate when the thermostat engages the other terminal 60 and when this occurs current will flow through the conductor 61, the switch 62, conductor 63, switch 64 which is in contact now with the member 25, the ground, thus completing the circuit to the magnetic means which will operate the armature 48 to lower the latch member 46 so that the tensioned spring 34 will move the lever 35 to the right in Figure 8. This action of the lever 35 will cause the arm 99 to engage the arm 101 and rock the shaft 98 so as to move the dog 93 to releasing position. Then the member 87 swings to the left, operating the lever 80 to cause the link 82 to open the other inlet and ex-

haust valves 8 and 12 so that water will flow into the right hand end of the cylinder and escapes in the left hand end thereof which forces the piston to the left. The movement of the member 87 will open the switch 62 and as the cross-head moves to the left it will reverse the position of the dampers and reset the parts to the position shown in Figure 8, the engagement of the projection 24 with the collar 71 causing the rod 76 and the bellcrank 75 to move the dog 72 to releasing position so that the member 37 will move forwardly into contact with the switch 59 and the other parts being moved to the position shown in Figure 8.

It is thought from the foregoing description that the advantages and novel features of the invention will be readily apparent.

It is to be understood that changes may be made in the construction and in the combination and arrangement of the several parts, provided that such changes fall within the scope of the appended claims.

What is claimed is:—

1. A hydraulic heat regulator for a heating plant comprising a reciprocating member, means actuated thereby for adjusting the dampers of the heating plant, a cylinder, a piston therein connected with the reciprocating member, means including inlet and exhaust valve means in each end for introducing water into the ends of cylinder and exhausting the water therefrom for reciprocating the piston, latchable spring actuated means arranged in sets, one set acting to open an inlet valve in one end and an exhaust valve in the other end and the other set opening the other valves, thermostatic control means for releasing one or the other of the spring means to open its valves, sets of means for returning said spring means to latched position and closing the valves and means whereby the resetting means are operated by movement of the reciprocating member.

2. A hydraulic heat regulator for a heating plant comprising a reciprocating member, means actuated thereby for adjusting the dampers of the heating device, a cylinder, a piston therein connected with the member for reciprocating the same, means including inlet valves for connecting the ends of the cylinder with a water supply, means including exhaust valves for connecting the ends of the cylinder to exhaust means, a lever connected to one inlet valve and one exhaust valve, a second lever connected to the other inlet valve and exhaust valve, spring operated members for moving said levers to the valve opening position, latch means for holding the spring means in operative position, a third lever connected with the latch means, a pair of springs for moving the third lever in one direction or the other, a pair of levers connected with the reciprocating member and alternately tensioning the last-mentioned springs, magnetic latch means for holding the third lever against movement, thermostatic means for controlling the magnetic means, a second pair of levers connected with the reciprocating member for moving the spring means first mentioned to latch engaging position and means operated by the spring tensioning levers for controlling the circuit between the thermostatic means and the magnetic means.

3. A hydraulic heat regulator for a heating plant comprising a reciprocating member, means actuated thereby for adjusting the dampers of the heating plant, a cylinder, a piston therein connected with the reciprocating member, pipes

containing valves for supplying water to the ends of the cylinder, exhaust pipes containing valves connected with the ends of the cylinder, a lever connected to one inlet valve and one exhaust valve for actuating the same, a second lever connected to the other inlet valve and exhaust valve for actuating the same, spring members for moving said levers to valve opening position, latch means for holding the spring members in operative position, a third lever connected with the latch means, a pair of springs connected with the third lever for moving the same in one direction or the other according to which spring is tensioned, a pair of levers connected with the reciprocating member for first tensioning one spring and retracting the other spring and then tensioning said other spring and retracting the first spring according to the movement of the reciprocating member, magnetic latch means for controlling the movement of the third lever by a spring, a

circuit for said magnetic means including a thermostat and a pair of switches, means carried by the spring members for opening said switches when said spring members are actuated by their springs, a second pair of spring members having parts engaging the spring tensioning levers, a latch member for each of the last-mentioned spring members, means for moving the last-mentioned latch members to releasing position by the reciprocating member at the ends of the strokes thereof, a second pair of switches in the circuit closed by the second set of spring members when the same are actuated by their springs, projections on said second set of spring members for moving the valve operating levers to valve closing position and a pair of levers connected with the reciprocating member for returning the first set of spring members to latching position.

MARK OLSON. 20
